UNITED STATES PATENT OFFICE.

CURTIS HUSSEY VEEDER, OF HARTFORD, CONNECTICUT, ASSIGNOR TO THE VEEDER MANUFACTURING COMPANY, OF HARTFORD, CONNECTICUT, A CORPORATION OF CONNECTICUT.

MAGNETIC COUNTER.

Application filed August 14, 1922. Serial No. 581,693.

To all whom it may concern:

Be it known that I, CURTIS HUSSEY VEEDER, a citizen of the United States, residing in Hartford, in the State of Connecticut, have invented certain new and useful Improvements in Magnetic Counters, of which the following is a specification, reference being had to the accompanying drawings, forming a part hereof.

10 For many purposes, such as the counting of sheets of paper as they issue from a cutter or from a press, counters actuated through the closing of an electric circuit commend themselves because of the responsiveness of the circuit closing devices to the slight force of the moving object. On the other hand such counters, as heretofore constructed, have failed to give complete satisfaction in some cases because of the relative 15 sluggishness of movement of the electromagnetic devices energized by the closing of the circuit and depended upon to operate the counting mechanism. The core of a solenoid, for example, is relatively slow in 20 starting its movement because of its own inertia which must be overcome. Moreover, since the movement of the solenoid is a sliding movement the friction to be overcome results in sluggishness of movement. 25 Furthermore, when the core of a solenoid has been set in motion its own momentum sometimes brings about an overthrow of the counting mechanism. Since magnetic counters are often desirable when the speed 30 of counting is great, a speed of more than one thousand counts per minute not being unusual, the sluggishness referred to is particularly undesirable. In the effort to overcome the sluggishness of magnetic counters 35 it has been found that an electromagnetic device having an oscillating armature can be made very lively, that is free from sluggishness, in operation, especially when the spring tension, which tends to return the 40 armature to its initial or zero position, is properly applied to the armature and the armature is properly supported in relation to the field of the magnets and the mechanical devices through which the movement of 45 the armature is made to operate the counting mechanism, are properly constructed, while the tendency of the rapidly oscillating armature to cause an overthrow of the counting mechanism is counteracted by a proper construction of the transmitting mechanism. 50

The present invention is intended to overcome the difficulties heretofore found to be incident to the use of magnetic counters and is concerned particularly with the mounting of the oscillating armature, the application of the torsional resistance to the armature and the transmission of the movement of the armature to the operating devices of the counting mechanism, and is concerned generally also with the construction of the magnetic counter as hereinafter described. The invention will be more fully explained hereinafter with reference to the accompanying drawings in which it is illustrated as embodied in a suitable form of the structure, and in which—

60 Figure 1 is a view in vertical, longitudinal section of a counter and its electromagnetic actuating mechanism which embodies in suitable form the several features of improvements to be described.

65 Figure 2 is a view of the same in horizontal section on the plane indicated on the broken line 2—2 of Figure 1, looking in the direction of the arrows.

70 Figure 3 is a view of the same in elevation as seen from the right hand in Figure 1, with the end plate of the casing removed.

75 Figure 4 is a view in vertical, transverse section on the plane indicated by the broken line 4—4 of Figure 1, looking in the direction of the arrows.

80 In the construction illustrated in the drawing the laminations *a* of the field magnets are forced under high pressure into the brass shells *b* and are held therein under compression by the brass end pieces *c* which are soldered into the shell, long rivets or rods *a'* being also passed through the laminations and the end pieces and having their 85 ends upset in the end pieces so as to insure the maintenance of the laminations under compression. End shell plates or thimbles *d*, soldered into the shells *b*, have tapped into them bolts *e* which receive intermediate nuts *e'* to bear against the end frame plates *f* and terminal nuts *e''* which bear against the casing end plates *g* which are properly fitted to the ends of the main casing *g'*. Other bolts *e''*, in the upper part of the casing, run 90 through both end plates *g* and support the counting mechanism *i*, which is made up as usual of a succession of number wheels *i'*, *i''*, etc., mounted upon a supporting shaft *i'''* and provided with transmission devices 95 100 105 110

of ordinary construction, as indicated at i^8 , by which the complete rotation of each number wheel effects a step by step advance of the number wheel of the next higher 5 nomination. A sight opening, through which the number wheels can be read, is indicated at g^2 .

The armature comprises a hollow shaft k which is mounted in suitable bearings provided therefor in the end frame plates f , and the armature plates mounted on the shaft and secured by nuts k^2 . The shaft has a preferably rectangular bore k^3 to receive a flat torsion spring k^4 which is corrugated at one end, to engage the bore of the shaft, and at the other end, as at k^6 , is bent to engage a slotted plate k^7 , which may be held adjustably against the frame plate f by a bridge piece k^8 secured to the frame 15 plate by screws k^9 , the rotation of the plate k^7 in one direction or the other serving to adjust the tension of the torsion spring.

To the end of the shaft k is clamped adjustably, as at l , one arm l' of a toggle lever l', l^2 , the arm l^2 being pivotally connected to an oscillating pawl frame l^4 which is mounted concentrically with the shaft i^7 and carries spring pressed pawls l^5 for co-operating with a ratchet wheel l^6 in co-operative 25 relation with the first number wheel i' . A hold pawl l^6 is also provided for cooperation with the ratchet wheel to prevent backward movement thereof. Buffers l^7 are secured to the supporting frame to cushion the arm 30 l' in its oscillations. It will be observed that the provision of the toggle lever between the oscillating armature and the counting mechanism insures the slowing of the movement of the pawl frame as the 35 armature approaches the limit of its movement so that the tendency of the counting mechanism to overthrow in the rapid movement of the armature is counteracted.

Suitable binding posts are provided, as at 40 m, m_1 , for the usual electrical connections. The circuits are arranged as usual in devices of this general character and need not be illustrated or explained herein.

It will be understood that various changes 45 in details of construction and arrangement can be made to suit different conditions of use and that, except as indicated in the ac-

companying claims, the invention is not limited to the particular construction and arrangement shown and described herein. 55

I claim as my invention:

1. A magnetic counter comprising counting mechanism, an electromagnetic actuating mechanism having an oscillating armature, and operative connections between the 60 armature and the counting mechanism including a toggle lever.

2. A magnetic counter comprising counting mechanism, an electromagnetic actuating mechanism having an oscillating armature, an arm secured to the armature, a ratchet wheel in operative relation with the counting mechanism, a swinging pawl frame and a second arm connecting the first named arm to the pawl frame and constituting 70 with the first named arm a toggle lever system.

3. A magnetic counter comprising counting mechanism, an electromagnetic actuating mechanism, a ratchet wheel in operative 75 relation with the counting mechanism, a swinging pawl frame, and a toggle lever connection between the actuating mechanism and the pawl frame.

4. A magnetic counter comprising counting mechanism, an electromagnetic actuating mechanism having an oscillating armature with a shaft having a rectangular bore, operative connections between the armature and the counting mechanism, and a torsion 80 spring within the shaft and having one end corrugated for engagement with the shaft and the other end secured to a relatively 85 fixed point.

5. A magnetic counter comprising counting mechanism, an electromagnetic actuating mechanism having an oscillating armature, with a shaft having a rectangular bore, operative connections between the armature and the connecting mechanism, a supporting 90 frame, a slotted rotarily adjustable plate clamped to the supporting frame, and a torsion spring having one end corrugated to engage the armature shaft and the other end bent to engage the slotted plate. 95

This specification signed this 7 day of August A. D. 1922.

CURTIS HUSSEY VEEDER.
